UNITED STATES PATENT OFFICE.

ANGELO BRIENZA, OF NEW YORK, N. Y., ASSIGNOR OF ONE-HALF TO CHARLES N. GREGG,
OF NEW YORK, N. Y.

WASHTUB-COVER.

1,272,203.

Specification of Letters Patent.

Patented July 9, 1918.

Application filed January 24, 1918. Serial No. 213,503.

To all whom it may concern:

Be it known that I, ANGELO BRIENZA, a subject of the King of Italy, and a resident of the city of New York, Port Richmond, 5 borough of Richmond, in the county of Richmond and State of New York, have invented a new and Improved Washtub-Cover, of which the following is a full, clear, and exact description.

10 The object of the invention is to provide a new and improved wash tub cover which is exceedingly strong and durable, not liable to warp or to bend out of shape and capable of sustaining considerable weight 15 thus permitting the use of the cover as a shelf when the wash tub is not in use. Another object is to provide a wash tub cover which is perfectly smooth at the top and devoid of sharp edges at the sides or bottom. 20

In order to accomplish the desired result use is made of a body formed of a piece of sheet metal bent over to provide a top, front and bottom, the top and bottom being 25 spaced apart and the body being provided at the top with side and back flanges bent onto the under side of the said bottom and providing sides and a back for the said body, a reinforcing frame held between the 30 said top and bottom and fastening means fastening the said frame, top, bottom and flanges together.

A practical embodiment of the invention is represented in the accompanying drawings forming a part of this specification, in which similar characters of reference indicate corresponding parts in all the views. 35

Figure 1 is a plan view of the wash tub cover as applied;

40 Fig. 2 is an inverted plan view of the same;

Fig. 3 is an enlarged transverse section of the same on the line 3—3 of Fig. 1;

45 Fig. 4 is an enlarged sectional side elevation of the same on the line 4—4 of Fig. 2;

Fig. 5 is a perspective view of the reinforcing frame; and

50 Fig. 6 is a face view of the sheet metal blank for forming the body of the wash tub cover.

The body 10 of the wash tub cover is 55 formed of a single piece of sheet metal 11 shown in Fig. 6. The piece of sheet metal 11 is bent over or doubled up to form a

top 12, a bottom 13, a front 14, a back 15 and sides 16 and 17, with the top 12 and bottom 13 spaced apart, as plainly indicated in Figs. 3 and 4. The back 15 and the sides 16 and 17 are provided with flanges 60 18, 19 and 20 bent over onto the under side of the bottom 13, the flanges having doubled-up edges 21, 22 and 23 to obviate sharp edges at the under side of the bottom 13. Within the hollow body 10 is arranged 65 a reinforcing member, preferably in the form of a U-shaped frame 25 having its middle portion 26 fitting against the back 15 and having its sides 27 and 28 fitting against the sides 16 and 17 of 70 the hollow body 10. The frame 25 is of a thickness corresponding to the distance between the top 12 and the bottom 13 of the hollow body 10 thus strongly reinforcing the hollow body at the sides and 75 back. The frame 25 is securely fastened in position in the hollow body 10 by the use of screws 30 which extend through the corresponding flanges 18, 19 and 20 and through the bottom 13 to screw into threaded apertures 31 formed in the members 26, 27 and 28 of the frame 25. The back member 26 of the reinforcing frame 25 is 80 also provided with apertures 32 for the passage of bolts 33 used for attaching the 85 hinges 34 to the hollow body 10, the hinges 34 being fastened by bolts 35 to the back board 36 of the wash tub cover, as plainly indicated in Figs. 1 and 2. It is understood that the said bolts 33 also pass through the 90 top 12, the bottom 13 and the back flange 18. The under side of the hollow body 10 is provided adjacent the front 14 with the usual bumpers 40, made of rubber or other suitable material, to cushion the wash tub 95 cover on the front edge of the wash tub.

It will be noticed that by the arrangement described, the wash tub cover can be cheaply constructed as no soldering is required and the several parts can be 100 securely fastened together by the use of the screws 30.

It will further be noticed that the top 12 of the wash tub cover as well as the front, sides and back are of unbroken continuity thus giving a very neat appearance to the cover when in use besides presenting no undesirable projections and insuring a snug fitting of the cover on the top of the wash tub.

By providing the inturned edges 21, 22 and 23 no undesirable projections are had on the under side of the wash tub cover.

The wash tub cover constructed as described is exceedingly strong and durable and can be readily used as a shelf during the time the wash tub is not in use. It will also be noticed that as no wood is used in the construction of the wash tub cover the latter is practically indestructible and is not liable to warp or to bend out of shape.

Having thus described my invention, I claim as new and desire to secure by Letters Patent:—

1. A wash tub cover, comprising a body formed of a single piece of sheet metal bent over to provide a top, front, back, sides and bottom, the top and bottom being spaced apart and the back and sides being provided with flanges bent onto the under side

of the said bottom, and a metal reinforcing frame extending between the said top and bottom and along the sides and back and screws extending through the said flanges 25 and the said bottom and screwing into the said frame.

2. A wash tub cover, comprising a body formed of a single piece of sheet metal bent over to provide a top, front, back, sides and 30 bottom, the top and bottom being spaced apart and the back and sides being provided with flanges having doubled up edges and bent onto the under side of the said bottom, and a metal reinforcing frame approximately U shape, the frame extending between the said top and bottom and fitting against the said sides and back and screws extending through the said flanges and the 35 said bottom and screwing into the said frame.

ANGELO BRIENZA.
